UNITED STATES PATENT OFFICE.

MAURICE J. BAER, OF ATTLEBORO, MASSACHUSETTS, ASSIGNOR TO THE BAER & WILDE COMPANY, OF ATTLEBORO, MASSACHUSETTS, A CORPORATION OF MASSACHUSETTS.

SNAP BUTTON.

Application filed January 19, 1922. Serial No. 530,327.

To all whom it may concern:

Be it known that I, MAURICE J. BAER, citizen of the United States of America, and resident of Attleboro, in the county of Bristol 5 and State of Massachusetts, have invented new and useful Improvements in Snap Buttons, of which the following is a specification.

This invention relates to snap buttons, 10 particularly cuff buttons, of the type having two members detachably connected together and adapted to be held in the button holes respectively of a cuff or other article when detached from each other. In buttons of 15 this type the detachable members customarily comprise shanks respectively extending through the button holes of the separable parts of the cuff or other article, the shanks having heads on their outer ends 20 and flanges on their inner ends, the flanges serving to retain the members in their respective button holes when separated.

In the manufacture of buttons of this type it has been proposed to provide the abutting 25 ends of the separable members respectively with a stud and a socket to hold the parts together. In such buttons the aforesaid flanges are relatively thick and their juxtaposed faces are somewhat convex thus presenting a substantial crack therebetween. 30 As a result of the combined thickness of the flanges and the crack therebetween the buttons hold the ends of the cuff too widely separated and present an unsightly appearance. 35 As a result of the convexity of the juxtaposed faces of the flanges the separable members have a tendency to roll on these surfaces, the central stud and socket not being adapted to prevent such relative motion 40 without being made unduly large, and this rolling motion obviously tends to separate the members; consequently the members frequently separate accidentally as when the wrist presses outwardly toward the button or when the cuff is drawn inwardly toward the wrist.

It has also been proposed to make buttons 45 of the aforesaid type in which one of the shanks is provided with a broad shallow cup having an inturned edge and in which the other shank is provided with a disk adapted to seat in the aforesaid cup and snap beneath said inturned edge. In such a button there

is no crack between the two parts but in order 55 for the inturned edge of the said cup to hold the said disk the combined axial dimensions of the cup and inturned edge is so great as to hold the ends of the cuff apart too widely and present an untidy appearance. Moreover, the method of holding the separable 60 members together, involving a disk snapping behind an inturned edge at the periphery of a cup, has numerous disadvantages chief 65 of which are the following. In such a construction it is practically impossible to provide a spring yieldingly to hold the separable members together and as a result the inturned edge must be relied upon for this purpose. Inasmuch as such an edge possesses little resiliency it is difficult to separate the 70 parts when new and after a short period of use the parts separate too easily as a consequence of wear. It is therefore necessary to shape the parts very accurately to function properly when new and even when so 75 shaped the useful life of the buttons is limited.

The objects of the present invention are 80 to provide buttons of the aforesaid type which are free from the unsightliness of prior buttons, which are axially compact at the junction between the two shanks, which present the appearance of a single annulus at said junction, in which the separable parts are free from the aforesaid rolling motion 85 and the shanks are held rigidly in adjustment, in which the separable parts are held from movement transversely of each other by means other than the means for detachably holding the parts together whereby the latter means may be made smaller and more 90 elastic to permit easy separation and to provide constant holding power throughout long periods of usage, which has substantially all the advantages of the old forms 95 of construction without their disadvantages, and which has in addition certain unique advantages as will be evident from this description and the accompanying drawings, in which,

Figure 1 is an axial section of a button constituting one embodiment of the invention;

Figures 2 and 3 are side views of the separable parts of the button;

Fig. 4 is a composite view showing one of

the heads of the button in end and side elevation respectively;

Fig. 5 is a composite view showing one of the button shanks with its cupped flange 5 in end and side elevation respectively;

Fig. 6 is a composite view showing the stud member with its flange in end and side elevation respectively; and

Fig. 7 is a composite view showing the 10 socket member in end and side elevation respectively.

A button made according to the present invention is characterized in that the shanks of the separable members are provided on 15 their inner ends with an interfitting stud and socket connection disposed in the axis of the button and also with male and female annuli surrounding the stud and socket connection in interfitting or nesting relationship; the male annulus being on the shank 20 carrying said socket and the female annulus being on the shank carrying the aforesaid stud, in the preferred construction, so that each shank has both a male and a female 25 part. By making the male annulus hollow it may serve as a housing for a detent adapted to engage the aforesaid stud and hold it in its socket, the detent preferably being in the form of a spring operative upon the 30 stud through an opening in the side of the socket. Said annuli can best be made in the form of flanges on the inner ends of the shank, one flange being cupped to receive the other flange, and the stud and socket 35 portions are preferably mounted on the shanks by means of flanges secured to the shank flanges. By making the shanks hollow, or at least the shank carrying the socket, the stud may be confined within the 40 shank or shanks thereby decreasing the size of the button in the region of its separable connection. In the preferred construction the hollow annulus for the detent is formed in part by the flange on the shank and in 45 part by the socket flange, the two flanges being joined together preferably at the outer periphery of the annulus.

The particular embodiment of the invention shown in the accompanying drawings 50 comprises the two separable parts A and B shown in side elevation in Figs. 2 and 3 respectively, the sectional view of Fig. 1 showing the parts in interconnected relationship. The parts A and B comprise heads 55 1 and 1' respectively upon which are ordinarily mounted ornamental caps not shown. The shanks 2 and 2' are hollow and are secured to the heads 1 and 1' by crimp connections 3 and 3'. The inner ends of the 60 shanks 2 and 2' are turned outwardly to form flanges 4 and 4', the flange 4 being cupped at 5. Figs. 1 and 2 show the preferred shape of the parts 1 and 2 before they are crimped together.

The axial stud and socket connection com-

prises the socket 6 having a flange 7 spaced from the flange 4' and hooked thereover at its outer periphery as indicated at 7 in Fig. 1. Thus the flanges 4' and 7 form a hollow annulus adapted to receive the detent spring 8 which yieldingly engages the head of the stud through openings 9 on the opposite sides of the socket 6. Fig. 7 shows the shape of the socket member before the flange 7 is crimped over.

The stud member, shown in end elevation in Fig. 6, comprises a rounded head 10, a reduced neck 11 and a base flange 12 adapted to fit into the cupped flange 4 of the stud member A. The shape of the neck 11 is such that the spring 8 tends to pull the stud into the socket by its engagement with the sloping portion of the neck, so that the parts are yieldingly held in close relationship as shown in Fig. 1 at all times.

All of the parts are preferably made of sheet metal stamped and pressed to form; and the permanent connections, such as 3 and 3', the connection between the flanges 4' and 7, and the connection between flanges 4 and 12, may if desired be soldered or welded although the connections are such that the parts are held together by virtue of their interlocking relationship.

As shown in Fig. 1 the tips of the edges of the flanges 4 and 7 are beveled off so that the appearance of the interfitting annuli (comprising flanges 4, 4' and 7) is a single annular protuberance whose outer periphery is smoothly rounded in cross-sectional contour. While the edge 5 of the female annulus may be turned inwardly sufficiently to snap over the male annulus when the parts are pressed together, it is preferably substantially tangent to the periphery of said male annulus so that the cupped flange 4 serves merely as a seat for the male annulus with the snap action confined wholly to the axial stud and socket. By making the flanges 4, 7 and 12 somewhat convex in cross-sectional contour the axial stud 11 is positioned approximately centrally of the button with its reduced neck in the central transverse plane of the spring 8.

As will be evident from the foregoing the separable parts are held tightly together by virtue of the axial stud and socket connection and the interfitting annuli surrounding the stud and socket, the spring 8 contributing to this result and at the same time constituting a yielding detent which permits easy separation of the parts when a straight pull is exerted on the separable parts.

I claim:

1. A snap button comprising two separable members each having a tubular shank, said shanks having interfitting male and female flanges on their inner ends, and stud and socket parts confined within the hollow shanks when the separable members are in-

terconnected, said parts having flanges secured to said male and female flanges respectively.

2. A snap button comprising two separable members each having a tubular shank, one of the shanks having an exterior flange on its inner end, a socket part disposed axially of said shank and having an exterior flange connected to said flange, the other shank having an exterior flange cupped to receive said flanges, and a stud adapted to fit into said socket, said stud having an exterior flange secured to said cupped flange.

15 3. A snap button comprising two separable members each having a tubular shank,

one of the shanks having an exterior flange on its inner end, a socket part disposed axially of said shank and having an exterior flange connected to said flange, the other shank having an exterior flange cupped to receive said flanges, and a stud adapted to fit into said socket, said stud having an exterior flange secured to said cupped flange, said first two flanges having a space therebetween, and a detent mounted in said space to engage said stud when the members are interconnected.

Signed by me at Attleboro, Massachusetts, this seventeenth day of January, 1922.

MAURICE J. BAER.
